Primary Examiner — Darlington Ly*(74) Attorney, Agent, or Firm* — Olson & Cepuritis, Ltd.;
Shawn E. Duckworth(57) **CLAIM**

The ornamental design for an exhaust silencer, as shown and described.

DESCRIPTION

The patent or application file contains at least one drawing executed in color. Copies of this patent or patent application publication with color drawing(s) will be provided by the Office upon request and payment of the necessary fee.

1. Exhaust silencer

1.1 is a bottom, rear, and right side perspective view of an exhaust silencer embodying our new design;

1.2 is a top, front, and right side perspective view thereof;

1.3 is a right side elevation view thereof;

1.4 is a left side elevation view thereof;

1.5 is a front elevation view thereof;

1.6 is a rear elevation view thereof;

1.7 is a top plan view thereof;

1.8 is a bottom plan view thereof;

1.9 is a top, rear, and right side perspective view thereof; and

1.10 is a rear and right side perspective view thereof.

1 Claim, 10 Drawing Sheets**(10 of 10 Drawing Sheet(s) Filed in Color)**(56)
